CALLING CARD

C. Miguel Breton Bringas, Apartado Postal 77-100,
Mexico City 10, Mexico

Filed Apr. 21, 1972, Ser. No. 246,515

Term of patent 14 years

Int. Cl. D19—05

U.S. Cl. D59—2 A

FIG. 1

FIG. 3

FIG. 1 is an isometric view of a calling card showing my new design;

FIG. 2 is a top plan view thereof, the bottom plan view being reversely similar;

FIG. 3 is an edge view taken from the left of FIG. 2.

I claim:

The ornamental design for a calling card, substantially as shown and described.
